[57] CLAIM

The ornamental design for an auxiliary vehicle brake
light, as shown and described.

DESCRIPTION

FIG. 1 is a perspective view of an auxiliary vehicle
brake light showing our new design;

FIG. 2 is a top plan view of the light thereof;

FIG. 3 is a front elevational view thereof;

FIG. 4 is a side elevational view thereof, the opposite
side being a mirror image;

FIG. 5 is a rear elevational view thereof;

FIG. 6 is a bottom plan view thereof; and

FIG. 7 is a perspective view of a second embodiment of
our new design;

FIG. 8 is a side elevational view thereof, the opposite
side being a mirror image;

FIG. 9 is a rear elevational view thereof;

FIG. 10 is a bottom plan view thereof.
